SEMAUTOMATIC TUNER DEVICE FOR
RADIO APPARATUS AND THE LIKERichard W. May, Cedar Rapids, Iowa, assignor to
Collins Radio Company, Cedar Rapids, Iowa, a
corporation of Iowa

Application May 23, 1946, Serial No. 671,686

6 Claims. (Cl. 192—142)

1

This invention relates to semi-automatic controls for rotatable shafts, and more particularly to a device for selectively operating a control or tuning shaft for radio apparatus and the like. To facilitate tuning of radio apparatus, such for example as a radio transmitter, it is desirable in some cases to have a semi-automatic device which actually turns the control or tuning shaft to a predetermined position even though the radio apparatus is equipped with conventional manual dials. With such manual dials, it is not possible in all cases to tune the equipment by a single adjustment of the tuning dial. In most cases, the dial is either turned too far or too little on the first movement, necessitating a gradual hunting for the exact setting corresponding to a particular frequency. If the radio apparatus is of the type having several tuning dials, there is considerable time consumed before all the dials are set on exactly the right points. In accordance with the present invention, each manual tuning dial is provided with a semi-automatic actuating mechanism so that merely by turning the dial manually to a given one of a series of settings, the subsequent actuation of the tuning shafts is accomplished automatically and with a maximum of accuracy in the final setting.

Accordingly, it is a principal object of this invention to provide a compact device of simplified construction for semi-automatic tuning radio apparatus.

Another object of the invention is to provide a device for selectively adjusting radio apparatus and the like, which device is motor driven and is arranged to stop the tuning shaft in any desired angular position corresponding to that of a manually operable calibrated dial.

It is a further object of this invention to provide a shaft control mechanism of the type employing a series of presettable stop rings and cooperating selector pawls in conjunction with a compact arrangement for instantaneously starting the driving motor when the usual manual tuning dial is first moved to a new setting, and for automatically opening the motor circuit when a stop ring is stopped by a selected pawl.

A feature of the invention relates to a shaft control mechanism of the type employing a series of presettable stop rings and cooperating selector pawls wherein each pawl is provided with spring means connected thereto so as to exert a continuous force on the pawl in a direction tending to bring it into locking engagement with its operating stop ring.

Another feature relates to the simplified me-

2

chanical arrangement and electrical circuit controls associated with a tuning dial device of the type having a series of presettable stop rings and cooperating selector pawls.

Another feature relates to an improved stop ring control assembly having means to facilitate the presetting of the individual rings of the assembly.

A still further feature relates to the novel organization, arrangement and relative interconnection of parts which cooperate to provide an improved semi-automatic tuning device for radio transmitters and the like.

Other features and advantages not specifically enumerated will be apparent after a consideration of the following detailed descriptions and the appended claims.

In the drawing which represents a preferred embodiment,

Fig. 1 is a side view of a radio tuning control device embodying the inventive features.

Fig. 2 is a sectional view along the line 2—2 of Fig. 1 viewed in the direction of the arrows.

Fig. 2A is a sectional view of Fig. 1, taken along the line 2A—2A thereof.

Fig. 3 is a view of the device as seen from the opposite side to that shown in Fig. 1.

Fig. 4 is a sectional view similar to Fig. 3, but taken along the line 4—4 of Fig. 2A.

Fig. 5 is a front elevational view of Fig. 1 with part of the supporting structure broken away to show certain interior parts more clearly.

Fig. 6 is a plan view of one of the stop ring drum spacers according to the invention.

Fig. 7 is an enlarged view of part of the stop ring drum assembly explanatory of the action of the spacers of Fig. 6.

Fig. 8 is a composite mechanical and electrical circuit diagram explanatory of the operation of the device according to the invention.

Fig. 9 is a composite mechanical and electrical circuit diagram of a modification of the invention.

There is shown in Fig. 1, a control shaft 1, which may be the rotatable shaft to which is attached the rotor plates 2 of a tuning condenser 3, such as conventionally used in radio equipment. In certain kinds of radio apparatus, because of the size or weight of the tuning elements and associated parts, it is necessary or desirable to provide them with motive power from an electric motor. At the same time, it is necessary to insure that the tuning control shaft be accurately oriented in its desired angular position. The problem is of even greater importance where the radio equipment, such for example as a large radio

transmitter, has a considerable number of individually settable tuning controls. In accordance with the present invention, these controls are each settable in a semi-automatic manner under control of a simple and easily calibrated knob or dial. With this arrangement, it is merely necessary to turn each calibrated knob manually to the desired setting, and the device thereafter acts automatically to rotate the corresponding tuning control shaft until the selected setting is reached.

The tuning control device according to the invention is arranged as a self-contained unit mounted between the front and rear end plates 10 and 11, which are rigidly united in spaced relation by the top plate 12 and bottom plate 13. The shaft 14 which is adapted to control the tuning shaft 1 is mounted in suitable bearings in end plates 10 and 11. A cylindrical stop ring drum 15 is keyed or otherwise fastened to shaft 14, so as to be rotatable therewith. A series of ten similar stop rings 16a-16j are mounted around drum 15 and capable of being individually adjusted around this drum to effect their respective presettings, whereupon they can then be locked to the drum so as to rotate as a unit therewith. The locking and unlocking of rings 16a-16j is controlled by thumb screw 17. Gear 18 is appropriately coupled to an electrical drive motor 33 (Fig. 5) and causes rotation of shaft 14 through slip clutch 19. Shaft 14 can be turned manually independently of motor 33 by knob 20.

The stop rings 16a-16j are so designed that when fixed in selected preset position with relation to shaft 14, they cooperate with the respective selecting pawls 21a-21j which are pivotally mounted on pawl shaft 22. A selected pawl moves into locking engagement with its respective stop ring only when shaft 14 is driven by motor 33 to a predetermined angular position which in turn is determined by the setting of the manual knob 27. Locking engagement between a pawl and its respective stop ring is accomplished when the stop lug 23a-23j of a selected pawl enters the associated slot 24a-24j of the stop rings.

Associated with the pawls is a cam barrel comprising a series of ten cams 25a-25j, keyed or otherwise fastened to cam shaft 26, so as to rotate as a unit therewith in accordance with the manual setting of the calibrated knob 27. Each cam 25a-25j has a slot or recess 28a-28j respectively which receives the riding portion of the coacting pawl, these riding portions being designated 29a-29j. Each pawl is biased by a corresponding one of a series of tension springs 30a-30j to rotate the pawls counter-clockwise as seen in Figs. 2 and 2A. The recesses 28a-28j in the peripheries of cams 25a-25j respectively are equally spaced and so arranged as to form a helical path around the cam drum assembly. The helical arrangement of the cam slots 28a-28j allows all of the pawls, except the selected one, to ride on the peripheries of their respective coacting cams. When the riding portion of the selected pawl engages the preset recess of its coacting cam, the stop lug of that pawl rides on the periphery of its cooperating stop ring until shaft 14 reaches its selected angular position, whereupon the stop lug enters the stop ring slot and causes tuning shaft 14 to stop instantaneously, whereupon the clutch 19 slips.

Referring more particularly to Figs. 2 and 2A, let it be assumed that it is desired to tune the

apparatus to a frequency corresponding to that represented by engagement of pawl 21j with its associated stop ring 16j. In Fig. 2, the shaft 14 is shown in such a position that the riding portion 29j rides on the periphery of cam 25j which allows stop lug 23j of this same pawl to clear the periphery of the associated stop ring 16j. Springs 30a-30j are anchored to any suitable support 31, there being one such spring for each pawl tending to urge it in a counter-clockwise direction as seen in Figs. 2 and 2A. To effect a new tuned position of shaft 14, dial knob 27 is now manually turned in either direction, for example counter-clockwise causing counter-clockwise rotation of the cam barrel. The dial 27a is calibrated in positions each corresponding respectively to a slot in one of the cams. Consequently, when recess 28j corresponding to the manual setting of knob 27 is directly beneath riding portion 29j, the associated spring 30j causes the portion 29j to enter recess 28j and allows the corresponding stop lug 23j to ride on the periphery of stop ring 16j. As soon as any pawl rotates clockwise as above described, it closes a power circuit through the driving motor 33 as will be described in detail in connection with Fig. 8. Shaft 14 is thereupon automatically rotated by motor 33 and continues to rotate until slot 24j in the periphery of ring 16j comes into registry with stop lug 23j. Spring 30j thereupon causes the stop lug to enter the slot 24j and causes shaft 14 to be stopped instantaneously. The arrangement is such that as soon as a pawl rotates counter-clockwise sufficiently to allow its stop lug to enter the stop ring slot, the motor circuit is opened as will be described in connection with Fig. 8.

If it is desired to retune shaft 14 to a different setting, it is accomplished in the same manner, as above described, namely, by manually turning knob 27 in either direction to the new position which mechanically forces pawl 21j to rotate in a clockwise direction to cause disengagement of the stop lug 23j from the slot 24j. The shape of the lugs 23a-23j and the shape of the lugs 29a-29j are such as to permit disengagement of the previously set pawl as soon as the knob 27 is manually turned, this shape being fully set forth and claimed in application Serial No. 515,250, filed December 22, 1943.

When shaft 14 is stopped by engagement of a stop ring slot with its associated preset pawl, slip clutch 19 through which gear 18 drives shaft 14, allows gear 18 to turn relative to the shafts. When shaft 26 is manually turned by knob 27 as above described, the previously set pawl is disengaged from its stop ring slot allowing shaft 14 to rotate. Clutch 19 is preferably of the type described in detail in the application of Arthur A. Collins, Serial No. 483,899, filed April 21, 1943, now Patent Number 2,409,192. This clutch is designed so that it serves to limit the torque delivered to the stop ring drum 15, while permitting the rotation of the drive motor after the stop ring drum has been selectively stopped. Its transmissible torque is substantially entirely a function of the spring (not shown) and is independent of varying inter-surface coefficients. While the drawing shows ten stop rings and ten respective pawls, each actuated by a corresponding cam, it is clear that a greater or less number may be employed depending upon the number of tuning positions of shaft 14.

Fig. 3 shows more clearly the means for driving shaft 14. The master shaft 32 driven by a suit-

able motor 33 carries a worm gear 34, which meshes with gear 18. Each of the selector pawls 21a-21j is aligned with its respective stop ring and selector cam, the pawls being suitably spaced axially by spacer discs 35a-35i. The two end collars 36 are keyed to shaft 22, so as to prevent axial movement of the cams on that shaft once they are assembled in the proper position thereon.

As shown more clearly in Fig. 4, stop rings 16a-16j are separated by intermediate spacer discs 37a-37i respectively. The drum 15 is made up of a series of annular segments 15a-15j equal in number to the number of stop rings. These drum segments together with the intervening discs 37a-37i are rigidly clamped to form a unitary barrel which is keyed or otherwise anchored to shaft 14. The end member 15j may be suitably keyed to shaft 14 so as to force the pile-up of segments rigidly against the face plate of clutch 19, which in turn is rigidly backed by nut 38 threaded on shaft 14. The outer margin of each of the drum segments 15a-15j is of reduced transverse thickness with respect to the transverse thickness of the stop rings, to allow limited axial movement of the stop rings and of the outer margins of the spacer discs, which movement is necessary in locking and unlocking the relative positions of the stop rings relative to the shaft 14. It will be seen from Fig. 4 that the spacer discs 37a-37i are rigidly clamped as a unit with the drum segments, by the shiftable annular clamping member 39, and the outer diameter of each spacer is greater than the outer diameter of the drum segments so as to provide a radially extending and springy margin which lies between each pair of adjacent stop rings. These spacer discs are also designed so as to facilitate angular presetting of the stop rings relative to shaft 14 when the stop rings are unlocked. One of these spacers is shown in detail in Fig. 6 and, in accordance with the invention, they provide clamping surfaces between the adjacent stop rings, while allowing those rings to be rotated manually with a minimum of frictional drag when the rings are unlocked. As shown more clearly in the enlarged view of Fig. 7, the cam drum segments 15a-15j are slightly thicker than the corresponding stop rings. Consequently, when the stop ring assembly is clamped, it causes the outer flexible margins of the spacer discs 37a-37i to be deflected toward the right. Upon release of the clamping pressure, these margins spring back towards the left thus slightly separating the stop rings by a positive separating force. By this arrangement, it is possible to unlock the rings and to rotate any ring to its preset position without affecting the previously preset position of any other ring, and shaft 14 can be manually rotated by knob 27 independently of clutch 19. This therefore reduces greatly the frictional load on the stop rings during their manual presetting. Nut 38, and annular clamping member 39 provide means for clamping the stop rings 16a-16j and spacer discs 37a-37i as a rigid unit on the drum 15. Thumb screw 17 which cooperates with locking stud 40 is threaded into shaft 14 as shown in Fig. 4, consequently rotation of screw 17 causes axial movement of stud 40, the direction of rotation of screw 17 determining whether the stop rings are locked or unlocked. The actual locking and unlocking of the stop rings is accomplished by the axial movement of the member 39 which is carried by a bar 41 passing through shaft 14 and actuated by the movement of locking stud 40. When in the unlocked

condition, face 42 of member 39, rests against stop shoulder 43. If thumb screw 17 is rotated in a clockwise direction, member 39 moves to the right (Fig. 4) and the clamping is increased until all stop rings are locked to the shaft 14. The pitch of the threads on locking stud 40 is so chosen that there is no tendency to rotate shaft 14 during either the locking or unlocking operation. In other words, the torque required to overcome the friction between the stop rings and their associated intermediate spacers is always greater than the torque required to rotate the locking stud 40. In order that friction be reduced to a minimum and shaft 14 be accurately positioned, it is mounted on ball bearings 44 and 45 in plates 10 and 11 respectively.

The cams 25a-25j are fixedly clamped to the cam shaft 26 by the force of nut 46 against sleeve 47 and shoulder portion 48 on shaft 26. Since shaft 26 carrying cams 25a-25j is manually rotated by manipulation of dial 27, frictional drag and wear are not factors of paramount importance and simple journal bearings are used. These bearings may be formed by extruding a portion of the plates 10 and 11.

As shown more clearly in Fig. 5 and as schematically illustrated in Fig. 8, each of the selector pawls has a downwardly depending lug 51 having a slot 52. Consequently, all the slots 52 are in alignment in a direction parallel to the shaft 14. Extending through the aligned slots 52 is a bail member 53, the position of which is determined by the position of the selector pawls. Attached to one end of the bail 53 is a downwardly depending insulator arm 54, which is adapted to engage the movable contact 55 of a switch 56. The movable contact 56 cooperates with a corresponding fixed contact 57, the contacts 55 and 57 when in engagement connecting the power supply such as the battery 58 in circuit with the armature of motor 33 and the field winding 59 thereof. The switch 56 may be suitably mounted on the plate 13 as shown in Fig. 5 and the arm 54 may pass through a suitable guide 60 also attached to this plate 13. Since the drum 15 is of the one-way motion type in the sense that the motor 33 drives the said drum 15 in only one direction, it is not necessary to provide any reversing control circuit for the motor. It will be noted that when any given pawl rotates counterclockwise (Figs. 5 and 8) to selective stopping position wherein the lug 23 fully registers with the slot in the associated stop ring, the arm 55 is moved downwardly as a result of the tension of the pawl spring 30, causing the contacts 55 and 57 to open thus opening the motor power supply. It will also be observed that so long as the pawls are riding on the cams and so long as the lugs 23 are not in registry with the cooperating stop ring slots, the arm 55 is held in a raised position thus maintaining the above-described power circuit for the motor closed. It will also be noted that immediately shaft 26 is manually rotated to start a new selection, the previously preset pawl is forced to rotate partially in a clockwise direction resulting a sufficient upward movement of the arm 54 to close the motor supply contacts 55 and 57. Consequently from there on, the motor 33 takes over and causes the rotation of the stop ring drum until the previously selected pawl registers with the appropriate stop ring slot.

If it is desired to change the set-up or tuning position of a stop ring on tuning shaft 14, the dial 27 is turned to select the pawl associated with 75 that stop ring which allows that pawl and stop

ring to come into locking engagement thereby slipping the clutch 19. The driving motor 33 is then stopped and thumb screw 17 rotated in a counter-clockwise direction placing the stop rings in the unlocked condition. Knob 20 is then rotated until the tuning shaft 14 is in the desired angular position which causes the same angular displacement of the pawl engaged stop ring. Thumb screw 17 is then rotated in a clockwise direction until the stop rings are caused to be 10 in the locked condition. The device then stops or sets the shaft 14 in this same angular position each time the same cam is selected. If desired, any number of new tuning positions or stop ring positions may be accomplished by repeating the 15 above procedure for each desired new position of the stop rings.

From the foregoing description, it will be clear that the entire sequence of operations required to tune shaft 1 to any desired position is controlled by the simple manual turning of the knob 27 to the desired position. The turning of this knob not only sets the cam barrel to position a selected pawl, but also automatically closes the motor circuit instantaneously to cause the rotation of the stop ring drum. When the selected pawl finally registers with the proper stop ring slot, the motor supply circuit is automatically opened and the shafts 1 and 14 are positively stopped in the desired position. If desired an additional contact 61 may be provided to control the circuit of a small electric lamp 62, so that when the arm 54 is moved downwardly under control of any of the pawls to open the motor circuit, it simultaneously closes a circuit through the lamp 62, thus giving a visual indication that the sequence of operations is complete.

In the foregoing description, the device is of the one-way type, that is to say the stop ring drum is designed to rotate in only one direction. In certain devices of this character, the stop ring drum is limited to a single complete rotation and is arranged to undergo reversals of rotation until the desired selective position is reached. For this purpose, it is necessary to employ a reversible motor for the stop ring drum. At the same time, it is necessary to provide a limit switch arrangement so that when the stop ring drum has reached one limit of travel without having completed the selected operation, its direction of rotation is automatically reversed until the desired selection is made. Such an arrangement is schematically shown in Fig. 9. For this purpose, in addition to the stop rings 16a-16j, there is another stop ring 16s which carries a dog 63 which is adapted to operate the movable contact arm 64 of a suitable limit-reversing switch 65. This switch may be of any well-known snap-action or toggle type so that when member 64 is engaged by dog 63, it is moved to one position or the other depending upon the previous direction of rotation of drum 15.

The parts of Fig. 9 bearing the same designation numerals as those of Fig. 8, function in the same manner. In Fig. 9, the motor 33 has two separate directional control windings 66, 67, whose circuits are controlled by the limit-reversing switch 65. In the particular position shown in Fig. 9, the drum 15 has just reached the limit of its clockwise rotation and has operated arms 64 into engagement with contact 68 which contacts therefore remain closed until the drum is about to reach the limit of its counter-clockwise rotation. If the present pawl is not reached when the drum 15 reaches the limit of its travel

in one direction, its rotation is therefore automatically reversed under control of switch 65 until the stop drum 15 reaches the selected position wherein the preset pawl 21 registers with the appropriate slot in its cooperating stop ring.

While certain specific embodiments have been described herein, various changes and modifications may be made therein without departing from the spirit and scope of the invention.

What is claimed is:

1. A device for selectively setting a control shaft of radio apparatus and the like, comprising a manually settable selector cam shaft having a series of selector cams, a plurality of shiftable stop pawls one for each cam, a plurality of stop rings arranged to be selectively stopped under control of a selected one of said pawls, each of said pawls having a toe and heel portion with the heel portion in coacting engagement with a corresponding one of said cams and with its toe portion in coacting engagement with a corresponding one of said stop rings, a motor for rotating said stop rings and said control shaft as a unit, manual means for rotating said cam shaft to move a selected one of said pawls to a preliminary stopping position, a common switch operating bail mechanically linked to all said pawls, and a power supply circuit for said motor completed through said switch and which is automatically closed upon initial manual rotation of said cam shaft and which remains closed until said selected pawl is moved to its final stopping position where it is in selective stopping engagement with its associated stop ring said selected pawl thereupon moving said bail to open said motor circuit.

2. A device for setting a radio control shaft and the like, comprising a manually rotatable cam drum, a motor driven stop ring drum, a plurality of shiftable pawls cooperating with said cam drum and said stop ring drum to stop said shaft in a selective position, a motor for driving said stop ring drum and said shaft, a power supply circuit for said motor, a switch for controlling said power supply circuit, an operating bail common to all said pawls and operated thereby, and means controlled by said bail for operating said switch.

3. A device for selectively setting a radio control shaft and the like, comprising a manually rotatable selector cam drum, a motor driven stop ring drum, a plurality of shiftable pawls arranged to be selectively set under control of said cam drum, said pawls coacting with said cam drum and said stop ring drum to stop said shaft in a selective position, all of said pawls being linked to a common operating bail, a switch for controlling the power supply circuit of said motor, and means including said pawls for operating said switch in response to movement of said bail.

4. A device for selectively setting a radio control shaft and the like, comprising a series of selective pivoted pawls, each pawl having a selecting lug and a stopping lug, a motor driven stop drum cooperating with said stopping lugs, a manually rotatable cam drum cooperating with said selecting lugs, a motor for driving said motor driven drum, a switch for controlling the circuit of said motor, means responsive to the initiation of rotation of the cam drum in one direction to move said pawls in one direction and thereby to close the circuit of said motor, and means responsive to a predetermined setting of both 70 of said drums to allow said pawls to move in an-

other direction and thereby to open the said motor circuit.

5. A device according to claim 4 in which said stop drum is arranged to undergo reverse rotations in arriving at its predetermined setting, and a limit reversing control switch is provided and is operated in response to said drum reaching the limit of its travel in either direction for automatically reversing the direction of rotation thereof until said setting is reached.

6. A device according to claim 4 in which said switch has an additional contact and an electric lamp is provided with a circuit controlled by said additional contact to cause said lamp to be lighted to produce a visual indication when the said 15
